UNITED STATES PATENT OFFICE

2,683,068

INTERLOCKING FULLY METAL GUIDED
EXTENSION TABLE SLIDE

Otto A. Beeck, Floral Park, N. Y.

Application September 13, 1952, Serial No. 309,456

3 Claims. (Cl. 311—71)

1

The present invention relates to extension tables and more especially to improvements in the slides used in connection with such tables.

It is an object of the present invention to provide slides for extension tables which have all the advantages of metal-on-metal slides without sacrificing the advantages inherent in the conventional wooden beam construction. It has been proposed to make extension table slides entirely of sheet metal. With slides of this kind, the table loses its character as a wooden furniture not only with respect to appearance and feel but also with respect to mechanical performance and sound because such all-metal slides tend to rattle or, when buckled, become inoperative. All-metal slide extension tables are more costly to manufacture than tables having wooden slides.

The slide construction according to the present invention uses the conventional wooden beam to provide the desired support and comprises relatively small and light metal slides of a special design attached to the wooden beams in a manner that does not materially weaken the beams. The metal slides according to the invention are in the form of light sheet metal rails of such cross-sectional configuration that they can be easily and inexpensively manufactured and attached to the wooden beams. The combination of the conventional wooden beam with the rails according to the invention completely eliminates the inconveniences connected with conventional wooden slides and caused by swelling, shrinking, and warping of the wood.

Further and other objects of the present invention will be hereinafter set forth in the accompanying specification and claims, and shown in the drawing which, by way of illustration, shows what I now consider to be a preferred embodiment of my invention.

In the drawing:

Fig. 1 is a vertical cross sectional view of an extension table slide system according to the invention, the section being taken along line I—I in Figs. 2 and 3;

Fig. 2 is a horizontal sectional view of a portion of the slide system shown in Fig. 1, the section being made along line II—II in Fig. 1;

Fig. 3 is a top view of a complete slide system according to the invention.

Like parts are designated by like numerals in all figures of the drawing.

Referring more particularly to the drawing, numerals 1, 2, and 3 designate three juxtaposed wooden slide beams for use in the conventional manner in connection with a table

10 having two permanent top sections, one of which is attached to beam 1 and the other to beam 3, and having two supplemental top sections adapted to be laid between the permanent sections when beams 1 and 3 have been moved in the direction of the arrows 20 and 21 in Figs. 2 and 3 relatively to the stationary beam 2, i. e. when the slide is fully extended. The table top sections are not illustrated because they do not form part of the present invention.

15 Each of the slide beams 1 and 3 has a longitudinal horizontal saw cut 6 and 7, respectively, on the side facing the center beam 2. The latter has two horizontal saw cuts, 8 and 9, one on each side. The saw cuts are made to receive horizontal portions of rails made of light sheet metal which will be described later. The horizontal portions of the rails are secured in the saw cuts by nails or pins 15 vertically driven into the respective wooden beam and through the horizontal rail portions.

20 The cross-section of all rails is the same and will therefore be described only with reference to rails 6' and 8''. Each rail has a track portion designated by numeral 16 for rail 6' and 18 for rail 8''. The track portions are bent at a right angle with respect to the horizontal rail portions. Each track portion is bent upon itself to produce a vertical U-shaped cross-sectional configuration. It will be noted that all rails used in the new table slides are alike and can be manufactured continuously and cut to the desired length from continuous rail strips. The last-bent portion of one rail closely fits between the legs of the U formed by the track portion of the adjacent rail.

25 One end of slide beam 1 is provided with a short guide rail section 6' which runs in a rail 8'' which extends from one end to the middle of center beam 2. A rail 6'' extends laterally from beam 1 over half of its length to the other end of the beam. The position of rail 6'' with respect to beam 1 is the same as that of rail section 6'. Rail 6'' runs in a rail section 8' extending laterally from the end of center beam 2 distal with respect to the end from which rail 8'' extends. By the aforesaid means beam 1 is guided and supported by the center beam 2 if moved half of its length in the direction of arrow 20.

30 A short rail section 9' extends laterally to the right in the views shown in the drawing, from one end of center beam 2 for guiding rail 7'' extending to the left from one half of the length of beam 3. A rail 9'' extends from beam 2 in the same manner as section 9' but from the one

half of beam 2 which is distal of the end of the beam on which section 9' is provided. Rail 9" is guided in a rail section 7' extending from the end of beam 3 distal of the end of beam 3 from which rail 7" extends. The arrangement of rail section 9' and rail 9" relatively to rail 7" and section 7', respectively, is such that beam 3 is positively guided and supported when moved in the direction of arrow 21 half of its length from the position shown in Fig. 3.

To limit movement of beam 1 in the direction of arrow 20, a pin 11 extends from beam 1 into a longitudinal groove 17 in beam 2 and abuts against a pin 19 extending from beam 2 into the groove 17 when beam 1 is moved outward to the full desired extent. For limiting movement in the opposite direction, a pin 22 extends from beam 1 into groove 17. Similarly, to limit movement of beam 3 in the direction of arrow 21, a pin 23 extends from beam 2 into a groove 24 in beam 3, pin 23 abutting against a pin 25 extending from beam 3 into groove 24 when beam 3 is pulled out to the desired extent. Movement in the opposite direction is limited by pin 25 abutting against a pin 26 extending from beam 2 into groove 24 when the relative position of beams 2 and 3 is as shown in Fig. 3.

A longitudinal recess 10 and 13 is provided in the sides of beam 1 and 3, respectively, facing the center beam 2, the latter having longitudinal recesses 12 and 14 facing recesses 10 and 13, respectively, to accommodate the track portions of rails 6', 6'', 8', 8'', 9', 9'', respectively.

While I believe the above described embodiment of my invention to be a preferred embodiment, I wish it to be understood that I do not desire to be limited to the exact details of design and construction shown and described, for obvious modifications will occur to a person skilled in the art.

I claim:

1. An interlocking fully metal guided extension table slide comprising at least two juxtaposed wooden beams having sides facing one another, a horizontal longitudinal saw cut in the side of each beam facing the side of the juxtaposed

positioned beam, and horizontal slide rails made of sheet metal, each rail having a horizontal portion and a vertical track portion extending longitudinally at a right angle from said horizontal portion, said vertical track portion being bent upon itself to form a vertical U-shaped cross-section, the horizontal portions of said rails being vertically spaced and individually inserted into and immovably secured in said saw cuts, said vertical track portions of rails inserted in saw cuts of sides of said beams facing one another being longitudinally slidably inserted into each other, one leg of the U-shaped cross-section of the track portion of one rail being placed between the legs of the U-shaped cross-section of the other rail, the vertical track portion of one of two cooperating slide rails extending downwards from the horizontal portion of the same rail and the vertical track portion of the other of the two cooperating slide rails extending upwards from the horizontal portion of the other rail.

2. An extension table slide as defined in claim 1, comprising pins extending vertically through said wooden beams and through the horizontal portion of said rails to hold the latter in their respective beams.

3. An extension table slide as defined in claim 1, comprising oppositely positioned longitudinal recesses in the sides of the beams facing one another, the recess in one beam accommodating the vertical track portion of the rail secured in the other beam.
